ICE CUBE MACHINE

Matthew J. Vlasic, Youngstown, Ohio

Application August 20, 1951, Serial No. 242,673

6 Claims. (Cl. 62—106)

1

This invention relates to an ice cube forming and dispensing machine and more particularly to a machine incorporating a freezing cycle of unusual length rendering the machine capable of operation with a relatively small and efficient compressor.

The principal object of the invention is the provision of an ice cube forming and dispensing machine incorporating a lengthy freezing cycle.

A further object of the invention is the provision of an ice cube forming and dispensing mechanism incorporating novel means for subjecting water to freezing action during continuous freezing cycle.

A still further object of the invention is the provision of an ice cube forming and dispensing machine incorporating the novel mechanical principle of subjecting a continuously arranged ice cube tray to freezing temperatures over a substantial period of time while at the same time advancing the continuous tray in a spiral motion to a point of dispensing the cubes therefrom.

The ice cube forming and dispensing apparatus disclosed herein has been designed to provide a simple, relatively inexpensive and efficient means of producing ice cubes continuously and particularly adapted for use in commercial establishments wherein a quantity of ice cubes is required in the serving of various beverages.

The ice cube machines heretofore known in the art have had the common disadvantage of either extremely limited capacity or the necessity of unusually large refrigerating mechanism in order to make the same workable. The present invention eliminates these difficulties in that it provides an adequate capacity of ice cubes and at the same time arranges the freezing portion of the machine so that the water filled continuous forming trays are subjected to the freezing temperatures for a lengthy freezing cycle.

The device herein disclosed also incorporates a simple mechanical movement preferably operated by solenoids, one of which is arranged to move the continuous ice tray and the other of which is arranged to discharge the ice cubes from the continuous tray.

With the foregoing and other objects in view which will appear as the description proceeds, the invention resides in the combination and arrangement of parts and in the details of construction hereinafter described and claimed, it being the intention to cover all changes and modifications of the example of the invention herein chosen for purposes of the disclosure, which do not constitute departures from the spirit and scope of the invention.

2

The invention is illustrated in the accompanying drawing, wherein:

Figure 1 is a side elevation with parts in cross section and parts broken away illustrating the ice cube forming and dispensing machine.

Figure 2 is an enlarged detail of the dispensing portion of the ice cube machine shown in Figure 1.

Figure 3 is a horizontal section on line 3—3 of Figure 1.

Figure 4 is a horizontal section on line 4—4 of Figure 1.

Figure 5 is a vertical section taken through the freezing portion of the machine shown in Figure 1.

By referring to the drawings and Figure 1 in particular it will be seen that an ice cube forming and dispensing machine has been disclosed which comprises a housing 10 having a tank 11 positioned therein for the reception of water which is supplied by a supply line 12 controlled by a float operated valve 13. A drain line 14 is provided to prevent overfilling of the tank 11 and it will be observed that the tank 11 is located above the bottom of the housing 10 and that it is partially supported in the housing 10 by a structural member 15 which includes a vertical journal 16 and a water-tight seal for rotatably positioning a cylindrical body member 17. The cylindrical body member 17 is flanged at its lower end as at 18. The cylindrical body member 17 is of smaller circumference at its upper end than its lower end, as best shown in Figure 5 of the drawings, and the lower portion thereof is preferably formed of non-metallic material.

A plurality of freezing coils 19 are disposed within the cylindrical body member 17 and a plurality of freezing coils 20 are disposed about the outer surface of the cylindrical body member 17 and spaced with respect thereto as also best illustrated in Figure 5. The freezing coils 19 and 20 comprise the evaporator in a mechanical refrigeration system including a compressor 21 and condenser (not shown) as known in the art.

By referring to Figures 1 and 5 of the drawings it will be seen that the lower portion of the body member 17 is preferably formed separately from the upper portion thereof and from a material such as a molded plastic or the like so that it will not act as a cold conductor. The upper portion of the body member 17 is preferably metallic and it will be observed that the freezing coils 19 and 20 are positioned adjacent this upper portion of the body member 17 and above the uppermost part of the tank 11.

By referring now to Figures 1 and 4 of the

drawings it will be observed that a drum 22 is mounted in the housing 10 above the tank 11 on a structural supporting member 23 incorporating a vertical journal 24 alongside the cylindrical body member 17. The drum 22 has a plurality of gear teeth 25 formed on a flange thereon and has a secondary flange 26 located thereabove and a plurality of circumferentially arranged, equally spaced, projecting bosses 27 positioned thereon immediately above the flange 26 as best shown in Figures 2 and 3 of the drawings. The circumferentially arranged bosses 27 are tapered at their uppermost edges, as best shown in Figure 3 of the drawings, and arranged so that they form a sprocket-like mechanism over which a continuous belt-like freezing tray 28 is positioned.

The belt-like freezing tray 28 has a plurality of cavities 29 in its bottom surface and a plurality of larger cavities 30 in its upper surface. The belt-like freezing tray 28 is endless and formed of a flexible material such as a synthetic rubber, the cavities 29 being adapted to register with the sprocket-like bosses 27 and the cavities 30 being adapted to be filled with water in the tank 11 and to retain the same through the freezing cycle and to the point of discharge of the ice cube in the machine.

The belt-like freezing tray 28 is spirally wrapped about the body member 17 and between the freezing coils 19 and 20 heretofore described and is passed under an idler 31 so that it is continuously fed onto the cylindrical body member 17 at the lower portion thereof immediately above the flange 18. The majority of the continuous belt-like freezing tray 28 is wrapped spirally about the body member 17 and is led from the upper portion thereof and turned a quarter turn by distorting the material thereof and passed about the drum 22, as best shown in Figures 1 and 2 of the drawings.

It will thus be observed that the cavities 30 will be filled with water when the tray 28 is passed beneath the idler 31 and into the tank 11 and fed onto the lower portion of the cylindrical body 17. It will then move upwardly in a continuous spiral pattern and at the top of the spiral pattern leave the cylindrical body member 17 and be twisted so that its normal upper surface becomes a side surface which is outwardly positioned with respect to the drum 22 about which it is then passed. Upon leaving the drum 22 it reassumes its normal position by passing under the idler 31 and is again fed into the spiral pattern being continuously formed on the cylindrical body 17.

In order that this operation may take place, means for rotating the drum 22 is provided and comprises a ratchet 32 which is normally spring urged against the gear teeth 25 by a spring 33 and adapted to be moved by a solenoid 34. It will be observed that operation of the solenoid 34 responsive to a remotely situated electrical switch (not shown) will move the drum 22 and hence the continuous belt-like tray 28 and that the movement will be imparted to the cylindrical body 17 through the belt-like tray 28 so that the hereinbefore described action results.

A secondary solenoid 35 is positioned on a supporting bracket 36 in the uppermost portion of the housing 10 and operably connected with a tapered plunger 37 which is positioned for vertical movement in registry with the spaced bosses 27 so that upon movement into the area between the continuous belt-like tray 28 and one of the bosses 27 the immediate portion of the 75

tray 28 will be distorted and moved outwardly sufficiently to cause the ejection of the ice cube in the cavity 30 adjacent thereto. The ice cubes being ejected from the machine are indicated by the letters C in the drawings.

By referring to Figures 2 and 4 of the drawings it will be seen that a tubular housing 38 is disposed about the belt-like tray 28 to properly guide the same during its travel between the drum 22 and the cylindrical body 17. It will also be observed that the tubular housing 38 is not refrigerated and that the cubes C in the portion of the continuous tray 28 leaving the freezing area of the cylindrical body 17 will have an opportunity to melt sufficiently to free them from adhesion in the cavities 30 of the tray 28 as they move toward the point of ejection therefrom, as heretofore described. The tubular housing 38 is not illustrated in Figure 1 of the drawings so as to enable a clearer understanding of the operation of the device to be had.

It will thus be seen that the several objects of the invention have been met by the ice cube machine shown and described herein.

Having thus described my invention, what I claim is:

1. An ice cube forming and dispensing machine comprising an endless belt-like tray having cavities therein, a cylindrical body member and a drum rotatably positioned on their vertical axes in horizontally spaced relation to one another, refrigeration means about said cylindrical body member, said endless belt-like tray positioned on said cylindrical body member in a spiral pattern and looped about said drum, a tank positioned about the lower portion of said cylindrical body member and means for moving said belt-like tray about said drum and cylindrical body member, said belt-like tray being turned one-quarter turn on said drum with respect to its position on said body member, and means for ejecting ice cubes from said belt-like tray on said drum.

2. An ice cube forming and dispensing machine including an endless flexible tray having relatively deep cavities in one side thereof and relatively shallow, oppositely disposed cavities in the opposite side thereof, a vertically standing, rotatable cylindrical body member, the majority of said endless belt-like tray being wrapped in a spiral around said cylindrical body member, a drum rotatably positioned in spaced relation to said cylindrical body member, a portion of said belt-like tray being passed around said drum, circumferentially arranged, spaced sprocket teeth on said drum for registry with the shallow cavities in said belt-like tray and mechanical means for moving said belt-like tray about said drum and cylindrical body member, a water filled tank, a portion of said belt being trained through said tank, and refrigeration means about said cylindrical body member for freezing the water in said larger cavities of said belt-like tray while the same is in spiral position on said cylindrical body member.

3. The ice cube forming and dispensing machine set forth in claim 2 and including a mechanically operated plunger for registry between said drum and said endless belt-like tray for ejecting ice cubes from said belt-like tray.

4. The ice cube forming and dispensing machine set forth in claim 2 and wherein an annular flange is formed on the lower portion of the cylindrical body member and wherein the belt-like tray is led onto the cylindrical body

member in engagement with said flange and moves in a spiral upwardly therefrom.

5. The ice cube forming and dispensing machine set forth in claim 2 and wherein the belt-like tray is positioned around said drum with the oppositely disposed cavities therein on a common horizontal plane.

6. The ice cube forming and dispensing machine set forth in claim 2 and wherein the belt-like tray is positioned around said drum with the oppositely disposed cavities therein on a common horizontal plane, and wherein a mechanical plunger is arranged for selective engagement be-

6
tween said belt-like tray and said drum for ejecting ice cubes from the cavities therein.

MATTHEW J. VLASIC.
